UNITED STATES PATENT OFFICE.

PIERRE PLANTINGA, OF CLEVELAND, OHIO.

COKE-OVEN.

1,255,047.

Specification of Letters Patent. Patented Jan. 29, 1918.

Application filed July 26, 1916. Serial No. 111,521.

To all whom it may concern:

Be it known that I, PIERRE PLANTINGA, a citizen of the United States, resident of Cleveland, county of Cuyahoga, and State of Ohio, have invented a new and useful Improvement in Coke-Ovens, of which the following is a specification, the principle of the invention being herein explained and the best mode in which I have contemplated applying that principle, so as to distinguish it from other inventions.

My invention relates to coke ovens and particularly to coke ovens having side walls which diverge from the charging toward the discharging end, certain features thereof, however, being particularly adaptable to and advantageous in connection with coke ovens in which the side walls of the coking chambers diverge and in which such chambers incline downwardly from the charging toward the discharging end.

The object of the invention is to provide a coke oven which will be economical of construction and efficient in its operation.

The annexed drawings and the following description set forth in detail certain means embodying my invention, the disclosed means, however, constituting but one of various mechanical forms in which the principle of the invention may be employed.

In said annexed drawings:—

Figure 1 represents a section of a fragmentary portion of a coke oven installation embodying my invention, taken upon the planes indicated by lines I—I in Fig. 5, the greater portion of such planes being parallel with the floor of the retort.

Fig. 2 represents a fragmentary transverse vertical section taken upon the plane indicated by the line II—II in Fig. 1 and viewed in the direction indicated by the arrows.

Fig. 3 represents a fragmentary longitudinal vertical section taken upon the plane indicated by the line III—III in Fig. 1 and viewed in the direction indicated by the arrows.

Fig. 4 represents a transverse vertical section taken upon the plane indicated by the line IV—IV in Fig. 1 and viewed in the direction indicated by the arrows.

Fig. 5 represents a transverse vertical section taken upon the plane indicated by the line V—V in Fig. 1 and viewed in the direction indicated by the arrows.

Fig. 6 represents a longitudinal vertical section taken upon the plane indicated by the line VI—VI in Figs. 4 and 5 and viewed in the direction indicated by the arrows.

Fig. 7 represents a longitudinal vertical section taken upon the plane indicated by the line VII—VII in Fig. 2 and viewed in the direction indicated by the arrows.

The illustrated embodiment of my invention comprises an outer casing or housing 1 of the required dimensions, such dimensions depending upon the number and size of the coking-chambers, as will be readily understood. Formed within the casing is a plurality of coking-chambers 2 whose sides, top 65 and bottom are formed of suitable tile 1^a abutting and joined with each other, the joints formed by the tile elements running in the general direction, that is parallel with the direction, of inclination of the chambers, 70 and at right angles thereto, as shown in Figs. 4 and 5. The upper end of each such coking-chamber is closed by means of a suitable removable closure 3 and communicating with such upper or rear end is a 75 charging duct 4 closed by a suitable closure 5, as shown in Fig. 4. Each coking-chamber is furthermore provided with a vertical gas take-off flue 6 connected with a suitable pipe 7 for conducting the gases formed to 80 the desired point.

The lower or front end of each chamber is closed by means of a suitable removable closure 8, as shown in Figs. 1 and 4.

The coal is charged through the charging 90 duct 4 into the chamber and when the coking operation is completed, the closures 3 and 8 are removed and the contents removed by pushing same from the rear out through the front end, as will be readily understood. 95

Adjacent to each side of each coking-chamber is a set of parallel combustion-chambers 9, these chambers also inclining and having a direction of inclination parallel with that of the general direction of inclination of the coking-chambers, as shown in Fig. 5. The upper or rear ends of each of the combustion-chambers comprising a given set, communicate with a vertical flue 10 which in turn communicates with a horizontal flue 11 which leads to the stack (not shown). This flue receives and takes off the gases of combustion formed in the combustion-chamber. Opposite the upper end of each combustion-chamber 9 is a shelf 12 and 100 105 110

side ledges 13, this shelf and ledges supporting a valve 14 which may be reached through an opening 15 normally closed by means of a removable closure 16, Fig. 5. The efflux of 5 the gases of combustion through the flues 10 and 11 are capable of regulation by means of these valves, as will be readily understood.

A longitudinal air duct 17, Figs. 2, 4 and 10 5, is provided and communicates by means of horizontal passages 18 with a vertical duct 19. The air duct 17 is usually connected with a recuperator (not shown) such as is ordinarily provided in this class of devices, as will be readily understood. One such duct 19 is located between the front ends of each two adjacent sets of combustion-chambers, as shown in Fig. 1, and communicates with a plurality of air inlets 20, 15 one of which is located adjacent to the lower end of each combustion-chamber, as shown in Fig. 5. These air ducts are controlled by valves 21, Fig. 2, which are located in passages 22 normally closed by closures 23 and 25 through which they may be reached for adjustment. The influx of air at these points is hence capable of regulation. An additional air inlet 24 is provided, as shown in Figs. 2 and 5, and also controlled by means 30 of a valve 25 located in a passage 26 and closed by a closure 27. This last-named air inlet communicates directly with the horizontal passage 18, as shown.

Opposite the lower ends of each set of 35 combustion-chambers is a vertical flue 28 whose lower end communicates with a gas duct 29 which itself is connected with a suitable source of fuel gas (not shown).

The device as above-described operates as 40 follows:

The gas from the duct 29 flows upwardly into the duct 28 and becomes mixed with air from the inlet 24. Additional air from the inlets 20 is mixed with the mixture of air 45 and gas first formed, and is then burned. These gases of combustion pass up through the combustion-chambers 9 and flow out through the flues 10 and 11. During such passage they heat the sides of the coking-chambers and effect the coking operation.

By arranging the apparatus, however, as described, that is, by permitting the initial combustion to take place at the lower or wider end of the coking-chamber, the maximum 55 temperature will be applied at this wider end where it is required, a larger mass of coke being located at this point and hence a higher degree of temperature being required. As the gases of combustion travel through the chambers or heating flues 9, and part with their heat, they are required, as they progress, to heat a volume of coal which grows smaller in the direction of travel of such gases, so that the mass of coal decreases as the gases become 60 cooler. By suitable regulation of the valves 65

the required initial temperature may be obtained and by the proper proportioning of the coking-chamber, a substantially uniform coking operation may be obtained, as will be readily understood by those skilled in the art.

Between each two adjacent sets of combustion-chambers is a partition wall 30, Figs. 1 and 6. This wall is built of suitable brick and the joints are made to run 75 horizontally and vertically. It will thus be seen that the joints of these partition walls and the joints of the adjacent side walls of the combustion-chambers lie in planes which intersect one another, the arrangement therefore being such that the adjacent joints "break" with each other. By means of this arrangement the cracking of these adjacent walls is minimized, as will be understood.

The side walls of all the coking-chambers 85 diverge in the same direction, as will be seen in Fig. 1. Part of the partition walls 30, as is shown in said figure, are rectangular in horizontal section, but certain of these walls, as for instance wall 31, are built so that 90 their sides will diverge in the direction opposite from that of the direction of divergence of the coking-chambers, as shown. By providing such a wedge-shaped partition wall at suitable intervals, the rectilinear form 95 of the entire installation may be preserved.

In the above-described manner, therefore, I obtain a coke oven installation which may contain any required number of coking-chambers, provide means whereby these coking-chambers and hence their contents are uniformly heated, and reduce cracking of the adjacent walls which expansion and contraction tends to produce, to a minimum. I am also, by means of the above-described 100 construction, enabled to incorporate in the installation, the diverging or wedge-shaped form of coking chamber, but still preserve the general rectilinear form of the entire 105 installation.

Having fully described my invention, what I claim and desire to secure by Letters Patent is:—

1. In a coke oven, the combination of an inclined coking chamber; a set of parallel combustion chambers arranged one above the other and adjacent to one side of said coking chamber; a vertical duct adjacent to the lower ends of the combustion chambers of said set; a gas supply for supplying fuel gas to said duct; a plurality of air inlets, one such inlet being located adjacent to the lower end of each said combustion chamber; a vertical duct communicating with the upper ends of the combustion chambers of each set; a waste gas flue connected with such last-named vertical duct; and a plurality of means operative independently of each other and respectively located adjacent to the upper ends of said 115 120 125 130

combustion chambers and adapted to control the exit of gases through said upper vertical duct.

2. In a coke oven, the combination of an 5 inclined coking chamber; a set of parallel combustion chambers arranged one above the other and adjacent to one side of said coking chamber; a vertical duct adjacent to the lower ends of the combustion chambers 10 of such set; a gas supply for supplying fuel gas to said vertical duct; a plurality of air inlets, one of such inlets being located adjacent to the lower end of each such combustion chamber; a vertical duct communicating 15 with the upper ends of all of the said combustion chambers of said set and connected with a waste gas outlet; said upper ends of said combustion chambers communicating directly with said upper vertical duct; and a plurality of independently operable valves respectively located opposite the upper ends of said combustion chambers, each valve being adapted to control communication between the combustion chamber 20 adjacent thereto and said upper vertical duct.

3. In a coke-oven, the combination of a plurality of laterally spaced coking chambers having vertical side walls converging from one end toward the other; combustion-chambers adjacent to each side wall of said coking chambers; and partition walls between the laterally adjacent coking chambers; part only of said partition walls having sides converging in a direction opposite 35 that of the side walls of said coking chambers.

4. In a coke-oven, the combination of a plurality of laterally spaced coking chambers having vertical side walls converging 40 from one end toward the other; combustion-chambers adjacent to each side wall of said coking chambers; and partition walls between the laterally adjacent coking chambers; part of said partition walls having 45 sides converging in a direction opposite that of the side walls of said coking chambers; the remainder of said partition walls having parallel sides.

Signed by me, this 14th day of July, 1916. 50

PIERRE PLANTINGA.
